UNITED STATES PATENT OFFICE

HARRY M. ROBERTSON, OF CLEVELAND, OHIO

KILN

Application filed September 22, 1930. Serial No. 483,530.

This invention relates to a continuous tunnel kiln.

One object of the invention is to provide an improved tunnel kiln which has a large capacity, is economical in operation and in which the ware is treated substantially uniformly.

Another object of the invention is to provide a tunnel kiln having an improved baffle which extends throughout the heating zone and which is of such construction that effective circulation of heat or heated air and saving of fuel consumption results.

Another object of the invention is to construct a tunnel kiln having at either side of the ware space combustion chambers each of which is provided throughout its length with a baffle constructed and arranged to direct the products of combustion below the ware, whereby such products are circulated through the ware upwardly and then downwardly to simultaneously heat the inner and outer portions of the ware.

Another object of the invention is to provide an improved tunnel kiln in which the heating medium is supplied to the ware space below the ware supports as they move through the heating zone of the kiln and the supports are constructed to permit circulation of the medium upwardly through the central portions of the ware and downwardly in contact with the outer portions thereof, whereby all portions of the ware are simultaneously and substantially uniformly burned.

Another object of the invention is to construct a tunnel kiln in which the inner side walls for the combustion chambers are of an improved construction to effect a circulation of the products upwardly through the central portion of the ware and downwardly in contact with the outer portions thereof to burn the ware in an efficient manner with minimum expenditure of fuel and minimum waste of unburnt or overburnt ware.

Another object of the invention is to provide for the combustion chamber of a tunnel kiln an improved wall section or member in which adequate circulation of the products of combustion takes place, and provision is

made to withstand relatively high temperatures for a long period of time.

Another object of the invention is to provide for the combustion chamber of a tunnel kiln a double walled member which adapts itself for use in forming a muffle, semi-muffle or open fire kiln.

Other objects of the invention will be apparent to those skilled in the art to which my invention relates from the following description taken in connection with the accompanying drawings.

Figs. 1 and 1a together are vertical sections through a kiln embodying my invention.

Figs. 2 and 2a together are horizontal sections through the kiln.

Fig. 3 is a transverse section, partly on the line 3-3 and partly on the line 3a-3a of Fig. 2a.

Fig. 4 is a section on the line 4-4 of Fig. 2a.

Fig. 5 is a section on the line 5-5 of Fig. 2, showing a loaded carrier in the ware space.

Fig. 6 is a transverse section, partly on the line 6-6 and partly on the line 6a-6a of Fig. 2.

Fig. 7 is a section on the line 7-7 of Fig. 2.

Fig. 8 is a front elevation of one of the baffle wall members or sections.

Fig. 9 is a section on the line 9-9 of Fig. 8.

Fig. 10 is a plan view of the member or section.

Fig. 11 is a side elevation of a ware carrier.

Fig. 12 is a plan view of a ware carrier.

In the drawings, 1 indicates a plurality of transverse steel beams adapted to be laid on a suitable flooring or foundation. 2, 3, indicate spaced uprights suitably secured to the beams 1, the uprights 3 being connected by horizontal channels 4. The channels 4 and beams 5, which rest on the uprights 2, form a support for elevated beams 6 extending transversely inwardly from the uprights 3. The beams 6 are of a length to leave a wide space between their inner ends for a purpose which will later appear. All of the parts above referred to are rigidly secured together to form a supporting frame work for the kiln walls which rest on the beams 100

6 and against the uprights 3, the latter being connected at their upper ends by tie rods 7 in a well known manner. 8, 8a, indicate sheet metal plates laid on the beams 6 and against the uprights 3 to form a bottom and outer facing walls for the refractory material, bricks, slabs and blocks used in the construction of the kiln side walls 9, to form a space extending from end to end of the structure and constituting contiguous heating and cooling sections or zones for the ware to be treated. The lower portions of the side walls 9 are extended inwardly to form at either side of the ware space benches 10. The benches 10 provide between them a relatively narrow passage through which portions of the ware carriers 11 (see Fig. 5) extend. By supporting the walls of the kiln on the elevated beams 6, the frames 12 and wheels 13 therefor of the carriers 11 may be conveniently mounted below the benches 10 exteriorly of the kiln to prevent deterioration and distortion of these parts due to heat. By preference, the carrier wheels 13 run on tracks 14 provided on the beams 1.

The outer portion 9a of the side walls 9 may be formed of insulating material, such as diatomaceous earth. The inner portions 9b of the side walls and benches 10 are preferably formed of fire brick. On top of the side walls 9 are refractory members 15 forming abutments for an arch 15', also formed of refractory material, such as fire bricks. That portion of the arch, which is over the heating zone, is preferably of sectional construction—see Figs. 3, 4 and 5—and may be insulated by a covering 15a of diatomaceous earth. The portion of the arch, which is over the cooling zone, is constructed to form a muffle 15b (see Figs. 1, 6 and 7).

16 indicates the heating or burning zone extending from a point adjacent the inlet end of the kiln, indicated at 17, to fire boxes or primary combustion chambers 18 disposed at either side of the ware space or passage. 19 indicates the cooling zone and 20 indicates an intermediate zone between the heating zone 16 and the cooling zone 19. The cooling zone extends from the zone 20 to the outlet for the ware, indicated at 21.

The inlet 17 and outlet 21 may be provided with doors (not shown) and tracks and transfer platforms or other means may be provided for conveying the carriers 11 from the outlet 55 to the inlet for re-entry into the kiln after being re-loaded.

Adjacent the inlet end at either side of the ware space, I provide a plurality of spaced pillars 22, which tend to prevent flow of cold air into the heating zone.

23 indicates the secondary combustion chambers (constructed as hereinafter set forth), extending along either side of the ware space, preferably throughout the heating zone 16, from the walls 20a forming the

intermediate zone 20 to the innermost pillars 22, their inner portions being in communication with the fire boxes 18, as clearly shown in Fig. 5.

Each fire box 18 is constructed of refractory material, such as fire brick, its walls 18a being incorporated in the adjacent side wall 9 and arch 15' in any well known manner to constitute a unitary structure. The fire boxes may be constructed to burn coal or similar fuel material, powdered coal, gas or oil. The construction shown is adapted for the combustion of oil or gas, but the equipment therefor is not shown. In the construction shown, the walls 18a of each box provide 75 sides, a top 18b, a bottom 18c, a front wall 18d and an upwardly inclined rear wall 18e, which directs the products of combustion upwardly into the adjacent combustion chamber 23. The front wall 18d is provided with an 85 opening 18' into or through which the fuel burner extends.

24 indicates a baffle or wall along either side of the heating zone 16 and extending from the upper surface of the adjacent bench 10 90 near its free edge to the arch 15' and forming with the adjacent bench, side wall 9 and arch 15' throughout the length of the heating zone, one of the secondary combustion chambers 23 already referred to. Each baffle comprises 95 a plurality of sections or members 24a disposed side by side, their lower ends being set or locked between the side walls of a channel 25 formed in and extending longitudinally of the adjacent bench 10 and their upper ends 100 resting against the face of a depending portion 15b of the outer arch section 15a, to which face the baffle member 24a may be sealed in a well known manner. As the top 105 surfaces of the benches 10 form the bottoms of the combustion chambers 23, and are subjected to high temperatures, these surfaces are formed of high heat resisting refractory material.

Each baffle member comprises an integral 110 structure formed of fire clay in any desired manner. Each such member consists of a main wall 26, side walls 27 and intermediate walls 28 spaced from each other and the side walls 27, arranged perpendicular to and 115 extending from end to end of said main wall 26 and a supplemental wall 29 of less length than the main wall 26 and connected to the walls 27, 28, to bridge the channels between them. The upper and lower edges of the wall 29 terminate preferably substantially 120 equal distances from the upper and lower edges of the walls 27, 28, and by preference the main wall 26 throughout its entire area, if desired, or any portion thereof is formed 125 with a plurality of ports 30. In the illustrated form of construction, that portion of the wall 26 below the lower edge of the supplemental wall 29 is formed with a plurality 130 of outlets or ports 30 for the flow or circula-

tion of the products of combustion into direct contact with the ware. As will be understood from Fig. 5, the ware supports 31 on the carriers 11 are mounted in a plane above the lower edges of the walls 29 and they are formed with openings 32 extending longitudinally throughout their central portions, so that the products of combustion are directed below these supports and rise through the openings 32 and through the central portion of the ware. The products and gases then, due to their cooling, tend to flow downwardly in contact with outer portions of the ware, so that the inner and outer portions of the ware are simultaneously and substantially uniformly subjected to the heating medium. By making the supplemental plate 29 of less length than the plate 26, the channels between the walls 27, 28, are open at their upper and lower ends to insure free circulation of the gases, as indicated by the arrows α , which circulation is enhanced by the flow of the products through the ports 30. The ports 30 above referred to serve two purposes, that is, they provide for the flow of the products of combustion and gases into the ware space as already described and those ports in the walls 26 of the baffle members near the inlet end of the heating zone provide for the discharge of the chilled gases and products of combustion from the ware space into the combustion chambers whereby they may be withdrawn from the latter under the influence of the suction means to be later described.

The baffle members are interlocked one with another, by means of tongue and groove elements, one side wall being formed with a longitudinal tongue 27a and the other side wall being formed with a groove 27b.

Within and at spaced points throughout each combustion chamber 23 I provide transversely arranged checkered walls 28a, which tends to retard the flow of the products of combustion, gases and heat to thereby prevent the formation of a current through the chamber under the influence of the suction means (to be later referred to) and permit these mediums to flow into the heating zone.

The frame 12 of each carrier supports a body member 33 on which one or more refractory members 34 rest. 35 indicates a plurality of transversely arranged, vertical slabs in spaced relation and supported on the members 34, and supporting the ware supports 31 in the manner above described. As shown in Fig. 12, the ware supports 31 on each carrier comprise two rows of slabs or plates formed of refractory material resting on the vertical slabs 35 in spaced parallel relation to provide an unobstructed passage 32 for the products of combustion from end to end of the batch or charge of ware on the supports 31.

The walls 20a at opposite sides of the in-

termediate zone 20 are of checkered formation and extend preferably upwardly from the benches 10 on which they are supported to the arch 15, and are disposed between the heating and cooling zones. By constructing the walls 20a as described, they serve as a reservoir or storage for heat so that the ware passing from the heating zone 16 to the cooling zone 19 is not subjected to a sudden drop in temperature and they also operate to prevent drift of the products of combustion and the gases into the cooling zone 19.

36 indicates a plurality of conduits leading from the outer end portions of the combustion chambers, through the side walls 9, two conduits for each chamber being shown. The conduits 36 are connected to a discharge main 36a and the latter is connected to the intake side of a suction means 37, such for example a power driven fan mounted in a casing 38 the function of which is to reduce the atmospheric pressure in the outer end portions of the two combustion chambers 23 and the heating zone to induce a flow of the products of combustion through both the chambers and the zone and the discharge or exhaust thereof.

39 indicates a plurality of nozzles leading into each combustion chamber 23, the purpose thereof being to supply air for combustion purposes according to the conditions desired in the ware space. The air supply for the nozzles 39 comprise conduits 39a connected to a main 40 which leads from the outlet of a power driven suction means 41 to be later referred to. The conduits 39a are also connected by conduits 42 with the outlet for the casing 38, so that when desired the products of combustion exhausted from the inlet end of the chambers 23 may be returned to the chamber 23 at a point adjacent the fire boxes 18. Each conduit 36 and 39 is provided with a valve or damper to control the flow therethrough in relation to each other; the main 40 may be provided with a valve to control the flow of air to the conduits 39a; the main 42 may have a valve 42a to regulate the flow of the products through it to the nozzles or to discharge them into a chimney 42b. The conduits at opposite sides of the kiln are connected by a pipe 42c.

43, 43a, indicate upper and lower conduits extending along either side of the cooling zone 19 above the benches and in opposed relation to the ware as it moves through the zone. Each lower conduit 43a rests on the adjacent bench 10; each upper conduit 43 rests on a refractory support 44 which is supported on the adjacent lower conduit 43a. The portions of the conduits 43, 43a, near the outlet 21 may be formed of metal; the remaining portions comprise sections formed of refractory material, such as fire clay. The outer end of the conduits 43, 43a, are con-

nected to air intake pipes 45; the inner ends of these conduits are connected to air discharge pipes 46. The pipes 46 are connected in a suitable manner to a conduit 47 which

- 5 in turn is connected to the intake of the suction means 41 comprising a power driven fan. The suction means 41 induces a flow of air into the intakes 45 and through the conduits 43, 43a, this air serving to absorb heat units 10 due to heat radiating from the ware as it moves through the zone 19, whereby the ware is cooled sufficiently to be discharged from the kiln. The muffle 15b is provided at its inner end with an outlet 48 which is connected 15 to the conduit 47 so that the heat in the muffle may be withdrawn therefrom.

The arch 15' may be provided with one or more openings 49 for pyrometers and also a ventilating opening 50 controlled by a damper 51. The arch 15' for the ware space between the heating zone 16 and the inlet 17 may be provided with an outlet 52 connected to a suction means (not shown) or one of the suction means already referred to, so that 25 cold air may be exhausted from this space.

Suitable means may be provided for sealing the zones 16, 19, 20, to prevent the escape of heat or intake of excess air into the cooling zones; for example, the vertical sides of the 30 benches 10 throughout the heating zone may be provided with projecting ribs 53 which co-operate with the members 34 to prevent flow downwardly of the products of combustion and heat; also the body member 33 is 35 provided on its sides with metal members 54 having depending flanges which run in sand or water held in troughs 56 to effect sealing of the ware space.

By regulating the air supplied to the chambers 23 the combustion of the fuel therein may be regulated at will, and where the baffle is constructed to provide open firing of the ware, as herein shown, the regulation of the air supply will also provide combustion 45 within the heating zone when desired.

By omitting the ports 30 in the walls 26 of the baffle sections, the combustion chambers constitute muffles for the products of combustion; and where a semi-muffle type of kiln is desired, any desired number of the 50 baffle members 24a may be of the muffle type (that is the walls 26 are not formed with ports 30) and any desired number of the remaining members may be provided with ports 30. By this arrangement, the products of combustion will not contact with the ware while passing through a portion of the heating zone.

To those skilled in the art to which my invention relates many changes in construction and widely differing embodiments and applications of the invention will suggest themselves without departing from the spirit and scope of the invention. My disclosures 60 and the description herein are purely illus-

trative and are not intended to be in any sense limiting.

What I claim is:

1. In a tunnel kiln having side walls and an arch forming contiguous heating and 70 cooling zones through which ware moves, carriers for moving the ware through said zones, benches extending throughout said heating zone at either side thereof, a sectional baffle extending from each bench to the 75 arch throughout said heating zone and forming with said bench, arch and adjacent side wall a combustion chamber, and a fire box incorporated in each side wall and forming a primary combustion chamber communicating 80 with the inner end portion of one of the first mentioned combustion chambers.

2. In a tunnel kiln having side walls and an arch forming contiguous heating and cooling zones through which ware moves, carriers 85 for moving the ware through said zones, benches extending throughout said heating zone at either side thereof, and a sectional baffle extending from each bench to the arch throughout said heating zone and forming 90 with said bench, arch and adjacent side wall a combustion chamber, a fire box incorporated in each side wall and forming a primary combustion chamber communicating with the inner end portion of one of the first mentioned 95 combustion chambers, and suction means connected with the outer end portion of each combustion chamber.

3. In a tunnel kiln having side walls and an arch forming contiguous heating and cooling zones through which ware moves, carriers for moving the ware through said zones, benches extending throughout said heating zone at either side thereof, the upper surface, 100 of each bench being formed along or adjacent its inner side with a longitudinal channel, a sectional baffle having its lower end fitted into said channel and extending from the bench to said arch throughout said heating zone and forming with said bench, arch and the adjacent side wall a combustion 110 chamber, and primary combustion chambers incorporated in said side walls and each communicating with one of the first mentioned 115 combustion chambers.

4. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adjacent bench, arch and side wall to form a combustion chamber and each section having side members abutting the side members of adjoining sections and an inner wall supported on said side members, and primary combustion chambers each communicating with the 120 125 130 135 140 145 150 155 160 165 170 175 180 185 190 195 200 205 210 215 220 225 230 235 240 245 250 255 260 265 270 275 280 285 290 295 300 305 310 315 320 inner end portion of one of the first mentioned combustion chambers.

5. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adjacent bench, arch and side wall to form a combustion chamber and each section having side members in interlocking relation with the side members of adjoining sections and an inner wall supported on said side members, and primary combustion chambers each communicating with the inner end portion of one of the first mentioned combustion chambers.

10 6. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adjacent bench, arch and side wall to form a combustion chamber and each section having side members abutting the side members of adjoining sections, intermediate members spaced from each other and said side members and an inner wall supported on said members, and primary combustion chambers each communicating with the inner end of one of the first mentioned combustion chambers.

15 7. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adjacent bench, arch and side wall to form a combustion chamber and each section having side members abutting the side members of adjoining sections and an inner wall supported on said side members and terminating at points remote from the upper and lower ends of said side members, and primary combustion chambers each connected to the inner end portion of one of the first mentioned combustion chambers.

20 8. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adj-

25 cent bench, arch and side wall to form a combustion chamber and formed with openings through which the products of combustion circulate into the heating zone, and each section having side members abutting the side members of adjoining sections and an inner wall supported on said side members and terminating at points remote from the upper and lower ends of said side members, and primary combustion chambers each communicating with the inner end portion of one of the first mentioned combustion chambers.

30 9. In a tunnel kiln having side walls and an arch forming contiguous heating and cooling zones, carriers for moving ware through said zones, benches extending throughout said heating zone at either side thereof, a baffle extending from each bench to the arch throughout said heating zone, said baffle comprising a plurality of sections having outer walls co-operating with the adjacent bench, arch and side wall to form a combustion chamber and formed with openings through which the products of combustion circulate into the heating zone, and each section having side members abutting the side members of adjoining sections and an inner wall supported on said side members and terminating at points remote from the upper and lower ends of said side members, said openings being located below the lower edge of said inner member, and primary combustion chambers each communicating with the inner end portion of one of the first mentioned combustion chambers.

35 10. In a tunnel kiln having side walls and an arch forming contiguous heating and cooling zones, carriers for moving ware through said zones, combustion chambers extending along either side of said heating zone, the inner wall of each of said combustion chamber comprising a baffle inclined upwardly and outwardly at its upper portion and formed with a plurality of openings in its lower portion, and primary combustion chambers each communicating with the inner end portion of one of the first mentioned combustion chambers.

40 11. In a tunnel kiln having side walls and an arch forming contiguous heating and cooling zones, carriers for moving ware through said zones, benches extending throughout said heating zone at either side thereof, a baffle extending from each bench to the arch throughout said heating zone and forming with the adjacent side wall and bench a combustion chamber, each said baffle being formed with a plurality of openings in its lower portion, and primary combustion chambers each communicating with the inner end portion of one of the first mentioned combustion chambers.

45 12. In a tunnel kiln, having side walls and an arch forming contiguous heating and cooling zones through which ware is moved,

benches extending throughout said heating zone at either side thereof, a baffle extending from each bench to the arch and forming with the bench, arch and side wall a combustion chamber, each said baffle being formed in its lower portion with an opening through which products of combustion circulate to said heating zone, and carriers having spaced vertical members and a ware support thereon above said opening in said baffle.

13. In a tunnel kiln, having side walls and an arch forming contiguous heating and cooling zones through which ware is moved, benches extending throughout said heating zone at either side thereof, a baffle extending from each bench to the arch and forming with the bench, arch and side wall a combustion chamber, each said baffle being formed in its lower portion with an opening through which products of combustion circulate to said heating zone, and carriers each having spaced vertical members and ware supports thereon above the openings in said baffles, said supports being arranged so as to leave a central opening communicating with the spaces between said first mentioned vertical members.

14. In a tunnel kiln having side walls and an arch forming contiguous heating, cooling and intermediate zones through which ware moves, carriers for moving the ware through said zones, benches extending throughout said heating zone at either side thereof, a baffle extending from each bench to said arch throughout said heating zone and forming with said bench, arch and adjacent side wall a combustion chamber, the walls of said intermediate zone forming a heat reservoir, and means for supplying heat to the inner ends of said combustion chambers.

15. In a tunnel kiln having side walls and an arch forming contiguous heating and cooling zones through which ware moves, carriers for moving the ware through said zones, benches extending throughout said heating zone at either side thereof, a baffle extending from each bench to the arch throughout said heating zone and forming with said bench, arch and adjacent side wall a combustion chamber, means for supplying heat to the inner end portion of each said combustion chamber, and suction means connected with the outer end portion of each combustion chamber and having its discharge or outlet connected to the inner end portion of each said chamber.

16. In a tunnel kiln having side walls and an arch forming contiguous heating and cooling zones, carriers for moving ware through said zones, benches extending throughout said heating zone at either side thereof, a baffle extending from each bench to the arch throughout said heating zone and co-operating with the adjacent bench, arch and side wall to form a combustion chamber, said baffles being formed with openings through

which the products of combustion circulate into the heating zone and permit the discharge thereof from the outer end of said zone, means communicating with the inner end portion of each combustion chamber to supply heat thereto, and suction means connected to the outer end of each chamber, the outlet from said means being connected to the inner ends of said chambers.

17. In a tunnel kiln having side walls and an arch forming contiguous heating and cooling zones, carriers for moving ware through said zones, combustion chambers extending along either side of said heating zone, the inner wall of each said combustion chamber comprising a baffle formed with a plurality of openings in its lower portion, primary combustion chambers each communicating with the inner end portion of one of the first mentioned combustion chambers, and suction means connected with the outer end of each said combustion chamber.

In testimony whereof, I have hereunto subscribed my name.

HARRY M. ROBERTSON.
